N. E. Hinds,

HORSESHOE.

No 23,027.

Patented Feb 22, 1859.

UNITED STATES PATENT OFFICE.

N. E. HINDS, OF COOPERSTOWN, NEW YORK.

IMPROVEMENT IN HORSE AND OX SHOES.

Specification forming part of Letters Patent No. 23,027, dated February 22, 1859.

To all whom it may concern:

Be it known that I, N. E. HINDS, of Cooperstown, county of Otsego, and State of New York, have invented new and useful Improvements in the Horse and Ox Shoe; and I hereby declare the following to be a full, clear, and exact description of the construction and operation of the same, reference being had to the accompanying drawings, making a part of this specification, and to the letters of reference marked thereon.

The nature of my invention, or the improvements thereof, consists only in constructing the heel-calks in a semicircular or curved form, with their corners turned inward or more toward the central points of the shoe, and also in locating both toe and heel calks somewhat away or back from the extreme forward point and heel ends of the shoe, thereby concentrating the calks more toward the centers of the shoes.

To enable others skilled in the art to make my shoes, I will next describe their construction and form.

Figure 1 of the drawings is a perspective view of the horseshoe. Fig. 2 is a one side or edge view of a shoe as fastened to the horse's hoof.

The ox or other animal shoe will be similar in construction, and will need no separate description.

The shoes are intended to be generally made by casting them in molds from molten iron, and the calks are to be chilled or hardened in the process of casting.

A, Fig. 1, shows the form of the toe-calk, which is partly curved and partly straight, and continues around the toe part of the shoe in either way to the ends of the ribs *c c*, for the purpose of strengthening the shoe. The toe-calks go off from the shoe a little back from the forward point thereof and in a backward sloping form, as may be seen at A, Fig. 2, for the purpose of preventing the toe-calks from cutting the heels of the forward feet or cutting onto the heel-calks by overreaching, and thereby knock off the calks, loosen the shoes, or bend, break, or tear them off.

B B, Fig. 1, are the heel-calks, constructed in a semicircular or curved form, with their corners turned inward, to prevent them from

cutting the opposite feet in case of interference. The heel-calks go off far enough forward of the hind end of the shoes as to secure them against being caught or stepped upon by the toe-calks upon the shoes of the hind feet, and they slope under on the outsides to render them less liable to cut the feet by treading upon them.

C C, Fig. 1, are ribs projecting from and downward from the shoe inside of the nail-holes, and are for the purpose of supporting and strengthening the shoes.

There are several very important advantages that ensue from constructing the calks of shoes in the manner herein specified aside from those above mentioned. In the first place, making them in a curved or circular form puts them into a kind of corrugated shape that renders them stronger and less liable to break; second, placing the calks away from the ends of the shoes makes them more central and shortens the leverage power for breaking the shoes; third, shortening the leverage power also lessens the power for wrenching and spraining the animal's legs or ankles, for if he steps one calk only upon a high stone or other obstruction, as they often do, his weight would stumble him over that calk, and the severity of the sprain that might ensue would be in proportion to the distance of the calk from the center of the foot; and, lastly, forming the calks farther from the ends and outsides of the shoes renders them less liable to strike stone and other obstructions, and consequently the shoes will not be so quickly loosened and worked off.

I am aware that shoes have been made with a flange or rib upon the outside edges thereof; therefore I do not claim the same, and, not intending to limit myself to an exact curved form, therefore—

What I claim as my invention, and wish to secure by Letters Patent of the United States, is—

The curved or semicircular form of the heel-calks, with the corners thereof turned inward or toward the central part of the shoe.

N. E. HINDS.
